UNITED STATES PATENT OFFICE.

GEORGE W. DONNING, OF EAST ORANGE, NEW JERSEY, ASSIGNOR TO
HARRY T. AMBROSE, OF ORANGE, NEW JERSEY.

ESCAPEMENT MECHANISM.

No. 826,483.

Specification of Letters Patent.

Patented July 17, 1906.

Application filed April 28, 1902. Serial No. 104,842.

To all whom it may concern:

Be it known that I, GEORGE W. DONNING, a citizen of the United States, residing at East Orange, in the county of Essex and State of New Jersey, have invented certain new and useful Improvements in Escape-
5 ment Mechanisms; and I do hereby declare the following to be a full, clear, and exact de-
scription of the invention, such as will enable
10 others skilled in the art to which it apper-
tains to make and use the same.

My invention relates to an improved feed mechanism for writing-machines, and partic-
15 ularly to a line-spacing device for flat-
platens type-writers; and it consists in the constructions, combinations, and arrange-
ments herein described and claimed.

The objects of my invention are to provide
means by which a progressive step-by-step
20 movement may be obtained, either automatic-
ally or manually, and which can be easily and conveniently adjusted for different
widths of steps.

A further object of my invention is to pro-
25 vide means for adjusting the writing-point
intermediary of the normal positioning of the
feed mechanism.

Referring to the accompanying drawings, forming a part of this application and in
30 which similar reference-symbols indicate cor-
responding parts in the several views, Figure
1 is a side elevation illustrating one embodi-
ment of my invention applied to a flat-
platens type-writer. Fig. 2 is a detail side
35 elevation showing the opposite side of the
type-writer. Figs. 2^a and 2^b are views re-
spectively in front and rear elevation of the
type-writer with parts omitted for clearness.
Fig. 2^c is a view in plan thereof. Fig. 3 is a
40 sectional elevation, on a larger scale, illus-
trating the feed mechanism. Fig. 4 is a plan
view of the feed mechanism, parts of the cas-
ing being broken away for clearness. Fig. 5
is a front elevation of the feed mechanism,
45 with parts of the casing removed. Fig. 6 is
a sectional elevation on the line 6-6 of Fig. 4.
Fig. 7 is a detail view of the loose and rigid
dog-plates. Fig. 8 is a detail side elevation
50 illustrating a preferred manner of pivotally
supporting the tracks. Fig. 9 is a sectional
elevation illustrating a preferred means for
adjusting the tracks. Fig. 9^a is a rear eleva-

tion of a part of the construction illustrated
in Fig. 9. Figs. 9^b and 9^c are views respec-
tively in front elevation and in plan of the 55
front portion of the track-frame and the
track-adjusting device. Fig. 10 is a detail
front elevation of the table, showing a por-
tion of the track in section, together with a
modification of its supporting means. Fig. 60
11 is a detail perspective view illustrating
the relative arrangement of the track and
platen, a line-space indicator and clamping
device being shown on the latter. Fig. 12 is
a detail view of a different form of line finder 65
and indicator. Fig. 13 is a detail plan view
illustrating a modified construction for ad-
justing the spring of the feed mechanism, and
Fig. 14 is a sectional elevation of the con-
struction illustrated in Fig. 13. 70

Referring to the drawings, A indicates a
suitable stand or table carrying at its re-
spective ends the plates b⁴ and b¹¹. A hinge-
plate b⁶ is secured in a rigid and fixed manner
to the plate b⁴ (see especially Figs. 1 and 8) 75
and pivotally supports a hinge-plate b⁸,
which is provided with slots b⁷. The track-
rails B are slidably secured by bolts b⁹ to the
hinge-plates b⁶ toward their rear portion and
are provided at their front end with a de-
pending portion b¹⁰, which rests upon the 80
front plate b¹¹. A pawl b¹⁰ is carried by the
track-rails in position to engage teeth b¹¹ on
the hinge-plate b⁸. The pawl may be actu-
ated either by gravity or by a spring b^{10a}. A 85
projection b^{11a} (shown carried by the pawl) is
arranged to engage the plate b⁴ and to main-
tain the pawl out of engagement with the
teeth b¹¹ when the track-rails B are in their
normal lowered position, but to permit en- 90
gagement of the pawl with said teeth when
the track-rails are elevated. If desired, the
projection b^{11a} could be carried by the plate b⁴
instead of by the pawl.

By having one portion of the hinge b⁴ se- 95
cured to the table-top and the other portion
to the track tilting of the track vertically is
permitted. To prevent a sliding movement
of the parts of the hinge when the track is
tilted, the pawl b¹⁰ is caused to take into the 100
teeth b¹¹ the moment the tilting movement
begins, the weight of the pawl causing it to
mesh with said teeth when the stud b^{11a} is
raised away from the plate b⁴. It is to be

understood that the locking-pawl device is arranged on each side for both rails.

An adjusting-block b^{18} , which is preferably cut out at its upper face to form approximately a V-shaped depression or slot b^{19} as deep as indicated by the dotted lines 19^b in Fig. 9^a and which is straddled by the track-frame, as presently to be described, the lower portion of said block being solid, is swiveled, as by a pin b^{22} , to a screw b^{14} , which latter is threaded in a portion b^{13} of the front plate b^{12} and provided with a knurled-head b^{16} . A screw b^{24} , carried by the adjusting-block, extends through a slot b^{23} in the front plate and constitutes means for guiding said adjusting-block during its adjustment by the screw b^{14} .

The depending portion b^{16} of the track-rails is provided with a recess which engages a tapered slot b^{19} , formed about the sides and top of the adjusting-block. It will be understood that by forming this slot with tapered walls the track-rails will be accurately adjusted when lowered to bring their depending portion b^{16} in engagement therewith. A spring-pressed pin b^{27} is carried by the adjusting-block in position to engage an opening b^{25} in the depending portion b^{16} of the track-rails for locking the latter in their normal lowered position.

The above-described construction provides means for adjusting the track-rails independently of the feed mechanism, hereinafter described, for the purpose of bringing the printing-point at any position intermediate of the positions controlled by the feed mechanism. It will be seen that the slots b^7 of the hinge-plate b^6 permit the track-rails to be adjusted by the adjusting-block b^{18} and that the pawl b^{10} will engage with the teeth b^{11} to prevent material shifting of the track-rails when elevated and that any shifting of the track-rails upon their elevation will be corrected when they are lowered by the engagement of their depending portion b^{16} with the walls of the tapered slot b^{19} .

Fig. 10 illustrates a modification of the means of properly positioning the track-rail and consists of stationary pins b^{31} , which are arranged to engage slots b^{32} , formed in the under portion of said rails. The slots b^{32} are shown constructed with tapered walls to insure proper engagement of the pins therein.

The track-rails B preferably extend past their pivotal support sufficiently to permit adjustment of the type-writer to the rear thereof in order that the combined weight of the type-writer and its rails may be substantially balanced about said pivotal support to facilitate elevation of the rails.

Any suitable buffer B^3 may be carried by the table in position to be engaged by the track-rails for preventing jar when the latter are elevated. In the arrangement illustrated there is a laterally-traveling carriage

A^2 for supporting the type-bars, ribbon mechanism, &c., and operated by letter-spacing mechanism. (Outlined in dotted lines in Fig. 2 and in full lines in Figs. 2^b and 2^c.) This carriage I will hereinafter refer to as the "writing mechanism." For supporting this laterally-traveling carriage or writing mechanism A^2 , I arrange guide-rails c , which extend between and are sustained by two standards C and on which travel rollers c^2 , Figs. 1 and 2, mounted on the carriage A^2 . The standards C and the connecting-tracks c constitute a second carriage A^3 , which is arranged to travel on the tracks B . It is to be understood, therefore, that I have in this construction two carriages, one, constituting the writing mechanism, A^2 , which travels on the rails c laterally over the platen for letter-spacing, and the other, A^3 , traveling on the rails B longitudinally over the platen for line-spacing. The present case, however, relates to the second carriage A^3 and feed mechanism for effecting its travel, and general mention herein of "carriage" and "feed" mechanism is to be understood to refer to the same rather than to the laterally-traveling carriage and its feed mechanism.

A plurality of antifriction-rollers c^4 are pivotally supported on each standard near its lower end and are preferably provided with a recessed periphery for engaging the track portion b^2 of the track-rails. Additional antifriction-rollers c^6 are carried by each standard in position to engage the under surface of a flange b^3 on the track-rails to prevent tilting of the carriage relatively to its rails. A shaft D is rotatably supported on each standard, preferably by bearing-screws d^2 , and carries at each end a feed mechanism arranged within a casing C^2 , carried by the adjacent standard. A tube d (shown surrounding the shaft D) may be secured at its respective ends to the casing C^2 for increasing the rigidity of the structure.

Within each casing C^2 a gear-wheel E and ratchet-wheel I are rigidly secured to the shaft D , and a gear-wheel G is loosely mounted on said shaft, and a spiral spring F has its respective ends connected to the gear-wheels E and G . The gear-wheel G is shown with its teeth engaging the pins h of a lantern-pinion H , these teeth being so formed that the gear-wheel G and pinion H constitute a self-locking mechanism. The pinion H is secured to a spindle h^2 , which extends through the standard C and is provided exterior thereof with a knurled head h^4 , by means of which the pinion H can be operated to rotate the gear-wheel G for varying the tension of the spring F .

A plate J is slidably supported between the gear-wheel E and ratchet-wheel I by means of screws j^2 , which extend through slots j^3 in said plate into studs j . The plate J is provided with a recess j^4 for bridging the shaft D

and carries a rigid dog j^5 . A spring j^8 , connected to the plate J and to a pin j^9 , carried by the standard, tends to retain said plate in its normal position with the rigid dog j^5 out of engagement with the ratchet-wheel I.

A plate M, carrying a loose dog m^9 , is mounted upon the plate J and provided with a yoke portion m^1 , bearing on the shaft D. A pin j^{12} on the plate J extends through a slot m^3 in the plate M and limits the downward swing of said plate M relative to the plate J. The slot m^3 is formed with an angularly-extending upper portion m^4 , which permits the plate M to be moved independently of the plate J for removing the loose dog m^9 from engagement with the ratchet I.

A lever N, pivotally supported on the stud j , is provided with a projection engaging a slot m^2 in the plate M and carries a rod n^2 . In the construction shown the rod n^2 extends between the levers N on the two standards C.

A shaft p , journaled in the type-writer basket and preferably extending at the rear thereof, carries a tripper-arm O, arranged to engage the rod n^2 . A longitudinal general release-key P is shown secured on the right-hand end of the shaft p in position to be conveniently grasped simultaneously with the handle c^3 and the general release-lever P^3 , arranged in proximity thereto and which engages the transverse escapement mechanism P^2 on the laterally traveling or writing mechanism carriage A^2 , the details of which are more fully set forth and claimed in my co-pending application filed April 26, 1902, Serial No. 104,842. It will be understood, therefore, that by arranging the keys P and P^3 in proximity to the handle c^3 the operator can grasp said handle c^3 and with one finger operate said lever P and with another finger operate the transverse escapement general release-lever P^3 , and by then having both the carriage A^2 and the carriage A^3 free to travel positioning of either carriage (by moving the carriage A^2 laterally and the carriage A^3 longitudinally over the platen) at any desired point can easily and quickly be effected, and this necessitates only the use of the operator's one hand.

An arm K, pivotally supported on a stud k , secured to the standard C, is provided with a slot k^4 , which slidably embraces a pin j^{11} , carried by a flange or toe j^{10} on the plate J. A spring k^4 (shown connected to the casing C^2 and the arm K) tends to maintain said arm in its normal position. The arm K is provided with a dependent lug or projection k^5 , which is arranged to be engaged by a cam-plate L, suitably positioned on the base-plate of the carriage A^2 , Figs. 2^b and 2^c. If desired, the arm K may be provided with a knob K² to provide means for conveniently actuating it manually at any time. A spring m^6 , secured to the loose dog-plate M and to a pin m^8 on the standard C, tends to swing said plate M

upward about its yoke bearing on the shaft D. An adjusting-arm Q is secured to a spindle q^3 , journaled in the casing C^2 , the free end of the lever Q being shown provided with a plurality of steps q^4 , either of which can be positioned to constitute a stop for limiting the upward swing of the loose dog-plate M. An arm R, rigidly secured to the outer end of the spindle q^3 , is provided with a handle r and with a projection r^2 , adapted to engage a series of openings in the casing C^2 . In the construction illustrated the series comprises three openings so arranged that when the projection r^2 is engaged in the lowest opening the arm Q will be adjusted to bring the step q^4 into position for limiting the upward swing of the plate M. When the projection r^2 is in the middle opening, the arm Q will be so adjusted that the step q^4 will constitute a stop for limiting the upward swing of said plate M; and when the projection r^2 is in the top opening of the series the arm Q will be raised out of the path of the plate M during the upward swing of the latter. If desired, the spindle q^3 , which carries the arm Q, could be pivotally supported on the rigid dog-plate J, and in such construction it will be necessary to provide slots in the casing C^2 for the spindle q^3 and projection r^2 . The adjusting-arm Q thus constitutes an adjustable stop for limiting the swing of the loose dog-plate M to produce single spacing, double spacing, or any larger spacing desired.

The operation of the feed mechanism is as follows: The spring F having been placed under proper tension by means of the pinion H tends to rotate the gear-wheel E, which meshes with the rack b on the track-rail. The gear-wheel E is normally held from rotation under the action of the spring F by the engagement of the loose dog m^9 with the ratchet-wheel I. Upon shifting the type-writer basket—that is, the carriage or writing mechanism A^2 —back along the transverse rails c to position said carriage A^2 at its starting-point at the left of the center of the platen for starting a line the cam-plate L will engage the lug k^6 on the arm K and swing said arm about its pivotal support, thereby shifting the plates J and M to the left (see Fig. 3) sufficiently to throw the rigid dog j^5 into engagement with the ratchet-wheel I and to release the loose dog m^9 from engagement with said wheel. When the parts are brought to this position, the wheel I will have the very slight rotation necessary to bring its adjacent tooth against the rigid dog j^5 , and the loose dog-plate M will be swung upward, by means of the spring m^6 , until stopped by its contact with the adjusting-arm Q, which latter can be set for single, double, or larger spacing, as previously described. Upon release of the cam-plate L from the lug k^6 the spring j^8 will act to return the plates J and M to their normal right-hand position, thereby

throwing the loose pawl m^9 into engagement with the ratchet-wheel I and releasing the rigid pawl j^5 therefrom. The spring F will then act to rotate the gear-wheel E and 5 ratchet-wheel I to produce travel of the standards along the track-rails B until the loose dog-plate m^9 has been carried to its lowest normal position by the rotation of the ratchet-wheel I, when the wheels E and I will be 10 locked against further movement.

To effect general release of the feed mechanism, the key P is actuated to cause shifting of the rod n^2 by the tripper-arm O. Such shifting of the rod n^2 will swing the levers N 15 about their pivotal supports j and draw the loose dog-plates M to the left (see Fig. 3) sufficiently to release the loose dogs m^9 from engagement with the ratchet-wheels I. During such movement of the plates M the pins 20 j^{13} , carried by the plate J, will traverse the angularly-extending upper portion m^4 of the slot m^3 in the plate M, and thereby permit the movement of the plate M without any motion of the plate J. It will thus be seen that 25 upon actuation of the key P both the rigid dog j^5 and loose dog m^9 will be held out of engagement with the ratchet-wheel I and the feed mechanism thereby released for free movement along the track-rails.

It is to be understood that initially the carriage A³ is positioned at a particular point by first operating the general release-lever P and moving said carriage to the line where the type-writer is to print. When the writing-mechanism carriage A² has traveled 30 across the platen and completed a line or such portion thereof as may be desired, said carriage A² is shifted back to its starting-point and there the cam-plate which it carries, as already stated, engages the lug k^5 on the arm K, which operates the feed mechanism of the carriage A³ and, under the action of the propelling-spring F, said carriage A³ is moved to the position of the next line. In 35 this manner, as will readily be understood, I secure an automatic operation of the feeding of said carriage A³ by the particular positioning of the carriage A². If, however, it is desired to secure operation of said feed mechanism for line-spacing otherwise than in the automatic manner described and also without operating the general release-lever P, the operator moves said arm K by hand by drawing 40 forward on the knob k^2 on said arm K, which operates said arm and its connecting parts in 45 the same manner as when it was actuated automatically, as aforementioned.

To provide means for printing in longitudinal columns, (from top to bottom,) suitable 50 connections may be provided for actuating the dog-plates from the universal bar of the type-writer. For example, a bell-crank lever may be secured to the dog-plate and provided with a rod extending in position to be 55 actuated by a depending finger carried by the

universal bar. Such finger would preferably be adjustably held in order that it can be thrown out of operative position when desired.

Fig. 11 illustrates a line-indicator attached 70 to the platen in any desired manner and which may serve also as a clamp for retaining the writing material and manifolding material in position.

Fig. 12 illustrates a line-finder U, which is 75 designed to be secured to the under side of the type-writer basket. This device comprises a lining-up strip u, slidably supported in guides u^2 and carrying a pin u^6 , which is engaged by the slotted portion of a lever u^3 , a spring u^7 being provided for returning the parts to their normal retracted position upon release of the lever u^3 . The strip u is provided with an indicating edge u^1 , which is brought directly to the printing-point upon 85 actuation of the lever u^3 .

Figs. 13 and 14 illustrate a modified construction for varying the tension of the springs F. In this modification the gear-wheel G and pinion H are discarded and a 90 pinion S' is arranged in mesh with the gear-wheel E. A spindle s has secured thereto the pinion S' and a knurled head s^3 , which latter is provided with teeth s^7 , which are spring-held in engagement with teeth s^8 , carried by 95 the standard C. A spring s^5 , bearing between a head s^2 on the spindle s and a flange s^6 on the knurled head s^3 , acts to hold the teeth s^7 and s^8 in engagement.

From the above construction it will be understood that the knurled head s^3 can be pulled out to disengage the teeth s^7 and s^8 and then turned to cause rotation of the pinion S' and gear-wheel E for varying the tension of the spring F. When the spring F has been 105 properly adjusted, the knurled head s^3 is released and pressed inward by the spring s^5 to bring its teeth s^7 into locking engagement with the teeth s^8 on the standard C, thereby preventing unwinding of the spring F. 110

While I have described my invention as applied for effecting longitudinal movement or line-spacing in a flat-platen type-writer, it is obvious that it may be employed with round-platen type-writers or other forms of writing-machines for effecting either transverse or longitudinal movement. 115

Having thus described my invention, what I claim as new, and desire to secure by Letters Patent, is—

1. In a writing-machine, the combination of a platen, horizontally-arranged track-rails adjustably supported adjacent said platen, a carriage mounted to travel horizontally on said rails, writing mechanism supported on and movable with said carriage, feed mechanism carried by said carriage, propelling means connecting with said feed mechanism constructed to effect spacing thereof along the rails, and means independ- 125 130

ent of said propelling means and constructed to adjust said track-rails longitudinally, whereby the writing mechanism can be brought to print at points along the platen intermediate of the spacings of said feed mechanism, substantially as described.

2. In a writing-machine, the combination of a platen, horizontally-arranged track-rails adjustably supported adjacent said platen, a carriage mounted to travel horizontally on said rails, writing mechanism supported on and movable with said carriage, feed mechanism carried by said carriage, propelling means connecting with said feed mechanism and constructed to engage said rails to effect spacing of the carriage thereon, and means independent of said propelling means and constructed to adjust said track-rails longitudinally, whereby the writing mechanism can be brought to print at points along the platen intermediate of the spacings of said feed mechanism, substantially as described.

3. In a writing-machine, the combination of a platen, horizontally-arranged track-rails adjustably supported adjacent said platen, a carriage mounted to travel horizontally on said rails, writing mechanism supported on and movable with said carriage, feed mechanism carried by said carriage, propelling means connecting with said feed mechanism and constructed to effect spacing thereof along the rails, means coöperating with said feed mechanism and constructed to vary the size of its spacing, and means independent of said propelling means and constructed to adjust said track-rails longitudinally, whereby the writing mechanism can be brought to print at points along the platen intermediate of the spacings of said feed mechanism, substantially as described.

4. In a writing-machine, the combination of a platen, horizontally-arranged track-rails adjustably supported adjacent said platen, a carriage mounted to travel on said rails, writing mechanism supported on and movable with said carriage, feed mechanism carried by said carriage, propelling means connecting with said feed mechanism and constructed to effect spacing thereof along the rails, means constructed for adjusting said feed mechanism to permit free travel of the carriage on the rails, and means independent of said propelling means and constructed to adjust said track-rails longitudinally, whereby the writing mechanism can be brought to print at points along the platen intermediate of the spacings of said feed mechanism, substantially as described.

60 5. In a writing-machine, the combination of a platen, track-rails supported adjacent said platen, hinge members by which said rails are sustained toward their rear ends and constructed to permit longitudinal adjustment thereon of said rails, a carriage mount-

ed to travel on said rails, writing mechanism supported on and movable with said carriage, feed mechanism carried by said carriage, propelling means connecting with said feed mechanism and constructed to effect spacing thereof along the rails, and means coöperating with said feed mechanism and constructed to vary the size of its spacings, substantially as described.

6. In a writing-machine, the combination of a platen, horizontally-arranged track-rails adjustably supported adjacent said platen, a hinge member by which each of said rails is sustained at the rear and constructed and arranged to permit said rails to have slight longitudinal movement thereon, a carriage mounted to travel horizontally on said rails, writing mechanism supported on and movable with said carriage, feed mechanism carried by said carriage and constructed to effect spacing thereof along the rails, spring means connecting with and constructed to actuate said feed mechanism, horizontally, and means coöperating with said feed mechanism and constructed to vary the size of its spacing, substantially as described.

7. In a writing-machine, the combination of a platen, horizontally-arranged track-rails adjustably supported adjacent said platen, a carriage mounted to travel horizontally on said rails, writing mechanism supported on said carriage, feed mechanism carried by said carriage and constructed to effect spacing thereof along the rails, spring means positively connecting with and constructed to actuate said feed mechanism and disposed on and movable with the carriage, manually-operative means constructed for varying the tension of said spring means, and means coöperating with said feed mechanism and constructed to vary the size of its spacing, substantially as described.

8. In a writing-machine, the combination of a platen, track-rails supported adjacent said platen, a carriage mounted to travel on said rails, feed mechanism carried by said carriage, carriage-propelling means connecting with said feed mechanism and constructed to effect spacing thereof along the rails and disposed on and movable with the carriage throughout its travel, a transversely-traveling writing mechanism movably supported on said carriage, and means carried by said traveling writing mechanism and arranged to engage with and operate said carriage-propelling means when positioned adjacent to one end of the writing-line.

9. In a writing machine, the combination of a platen, track-rails supported adjacent said platen, a carriage mounted to travel on said rails, feed mechanism carried by said carriage, carriage-propelling means connecting with said feed mechanism and constructed to effect spacing thereof along the rails and disposed on and movable with the carriage

- throughout its travel, a transversely-traveling writing mechanism movably supported on said carriage, means carried by said traveling writing mechanism and arranged to engage with and operate said carriage-propelling means when positioned adjacent to one end of the writing-line, and means coöperating with said feed mechanism and constructed to vary the size of its spacing.
10. In a writing-machine, the combination of track-rails, racks carried thereby, a carriage mounted to travel on said rails, gear-wheels disposed at either side of, and carried by, said carriage and constructed to rotate in unison and mesh with said racks, ratchet-wheels also operating in unison one with the other and secured to a common shaft with said gear-wheels, and dog mechanism constructed to permit a step-by-step rotation of said ratchet and gear wheels to permit intermittent feed of the carriage along said rails, and spring-actuated means disposed on the carriage, connecting with the dog mechanism and constructed to propel the carriage on the rails, substantially as described.
11. In a writing-machine, the combination of track-rails, racks carried thereby, a carriage mounted to travel on said rails, gear-wheels disposed at either side of, and carried by, said carriage and constructed to rotate in unison and mesh with said racks, ratchet-wheels also operating in unison one with the other and secured to a common shaft with said gear-wheels, and dog mechanism constructed to permit a step-by-step rotation of said ratchet and gear wheels to permit intermittent feed of the carriage along said rails, spring-actuated means disposed on the carriage, connecting with the dog mechanism and constructed to propel the carriage on the rails, and adjustable means coöperating with said dog mechanism for varying the extent of the step - by - step rotation of the ratchet-wheel, substantially as described.
12. In a writing-machine, the combination of track-rails, racks carried thereby, a carriage mounted to travel on said rails, gear-wheels carried by said carriage in mesh with said racks, ratchet-wheels secured to a common shaft with said gear-wheels, a plate carrying a rigid dog, means for actuating said plate to throw said dog into engagement with said ratchet-wheel, a loose dog supported on said plate for movement therewith, and means constructed to actuate said loose dog independently of its supporting-plate, substantially as described.
13. In a writing-machine, the combination of a platen, track-rails slidably secured on a pivotal support adjacent said platen, a carriage mounted to travel on said rails, adjusting means arranged to engage said rails in their normal, lowered position for longitudinally adjusting the same on their pivotal support, and means constructed to lock said rails in their adjusted position when elevated out of engagement with said adjusting means, substantially as described.
14. In a writing-machine, the combination of a platen, track-rails slidably secured on a pivotal support adjacent said platen, a carriage mounted to travel on said rails, adjusting means arranged to engage said rails in their normal, lowered position for longitudinally adjusting the same on their pivotal support, and coöperating means carried by said rails and their pivotal support and constructed to lock said rails in their adjusted position when elevated out of engagement with said adjusting means, substantially as described.
15. In a writing-machine, the combination of a platen, track-rails slidably secured on a pivotal support adjacent said platen, a carriage mounted to travel on said rails, adjusting means arranged to engage said rails in their normal, lowered position for longitudinally adjusting the same on their pivotal support, means constructed for detachably securing the rails to said adjusting means, and means constructed to lock said rails in their adjusted position when elevated out of engagement with said adjusting means, substantially as described.
16. In a writing-machine, the combination of a platen, track-rails slidably secured on a pivotal support adjacent said platen, a carriage mounted to travel on said rails, an adjusting-block, slidably supported and provided with a tapered recess arranged to be engaged by said track-rails when in their normal, lowered position, means for actuating said block for adjusting the track-rails on their pivotal support, and means constructed to lock said rails in their adjusted position when elevated out of engagement with said adjusting means, substantially as described.
17. In a writing-machine, the combination of a platen, track - rails disposed adjacent thereto, a carriage mounted to travel on said rails, feed mechanism carried by said carriage and including a plurality of dog-carrying members and spring operating means carried entirely by said carriage and connecting with said feed mechanism and constructed to propel said carriage for line-spacing, an actuating member connecting with one of said dog-carrying members, and a laterally-traveling body supported on said carriage and constructed to engage said actuating member and effect operation of the feed mechanism, substantially as described.
18. In a writing-machine, the combination of a platen, adjustable track-rails disposed adjacent thereto, a carriage mounted to travel on said rails, writing mechanism movably supported on said carriage, feed mechanism carried by said carriage, including spring operating means also carried by said carriage, connecting with said feed mechanism and exerting a constant tensioned move-

ment on said feed mechanism, and constructed to propel said carriage for line-spacing, and space-controlling mechanism constructed to govern operation of said feed mechanism, substantially as described.

5 19. In a writing-machine, the combination of a platen, track-rails disposed adjacent thereto, a carriage mounted to travel on said rails, adjustable feed mechanism carried by said carriage and including a plurality of dog-carrying members and spring operating means carried entirely by said carriage and connecting with said feed mechanism to exert a constant tensioned traveling movement on said carriage and constructed to propel said carriage for line-spacing, an actuating-lever member connecting with one of said dog-carrying members, and a laterally-traveling body supported on said carriage and constructed to engage said actuating-lever member and effect operation of the feed mechanism, substantially as described.

10 20. In a writing-machine, the combination of a platen, track-rails disposed adjacent thereto, a carriage mounted to travel on said rails, feed mechanism including a plurality of dog-carrying members and spring operating means carried entirely by said carriage, connecting with said feed mechanism, and exerting a constant tensioned movement on said feed mechanism and constructed to propel said carriage for line-spacing, an operating-bar carried by said carriage and connecting with one of said dog-carrying members, a traveling member supported on said carriage, and a key member mounted on said traveling member and constructed to engage said operating-bar and operate said feed mechanism, substantially as described.

15 21. In a writing-machine, the combination of a platen, track-rails disposed adjacent thereto, a carriage mounted to travel on said rails, adjustable feed mechanism including a plurality of dog-carrying members and spring operating means carried entirely by said carriage, connecting with said feed mechanism, and exerting a constant tensioned movement on said feed mechanism and constructed to propel said carriage for line-spacing, an operating-bar carried by said carriage and connecting with one of said dog-carrying members, a traveling member supported on said carriage, a key member mounted on said traveling member and constructed to engage said operating-bar and operate said feed mechanism, and adjustable space-controlling mechanism constructed to govern operation of said feed mechanism, substantially as described.

20 22. In a writing-machine, the combination of a flat platen, track-rails disposed adjacent thereto, a carriage mounted to travel on said tracks, carriage-propelling mechanism including spring actuating means carried solely by the carriage and connecting with said

feed mechanism and exerting a constant tensioned movement of said carriage, space-controlling mechanism, a plurality of dog-carrying members and a lever member connecting with one of said dog-carrying members of 70 said space-controlling mechanism and constructed to permit actuation of the same, and independent means also connecting with one of said dog-carrying members of said mechanism and constructed to disengage the 75 space-controlling mechanism from said feed mechanism to permit free movement of the carriage to any desired point, substantially as described.

23. In a writing-machine, the combination of a flat platen, track-rails disposed adjacent thereto, a carriage mounted to travel on said tracks, carriage-propelling mechanism including spring actuating means carried solely by the carriage and connecting with said 80 feed mechanism and exerting a constant tensioned movement of said carriage, space-controlling mechanism, a lever member connecting with said space-controlling mechanism and constructed to permit actuation of the 85 same, independent means also connecting with said mechanism and constructed to disengage the space-controlling mechanism from said feed mechanism to permit free movement of the carriage to any desired 90 point, a laterally-traveling member constructed to have movement into the path of said lever member to operate the same and effect operation of the feed mechanism where- 95 by limited spacing of the carriage is produced.

24. In a writing-machine, the combination of a flat platen, track-rails disposed adjacent thereto, a carriage mounted to travel on said tracks, carriage-propelling mechanism including spring actuating means carried solely by the carriage and connecting with said 100 feed mechanism and exerting a constant tensioned movement of said carriage, space-controlling mechanism, a lever member connecting with said space-controlling mechanism and constructed to permit actuation of the 105 same, independent means also connecting with said mechanism and constructed to disengage the space-controlling mechanism 110 from said feed mechanism to permit free movement of the carriage to any desired point, a laterally-traveling member constructed to have movement into the path of said lever member automatically to operate the 115 same and effect operation of the feed mechanism whereby limited spacing of the carriage is produced, substantially as described.

25. In a writing-machine, the combination of a flat platen, track-rails disposed adjacent thereto, a carriage mounted to travel longitudinally on said tracks, carriage-feeding mechanism including spring operating means carried solely by the carriage and connecting with said feed mechanism to exert a constant 125

2. In a writing-machine, the combination of a flat platen, track-rails supported adjacent thereto, a carriage mounted to travel longitudinally on said tracks, carriage - feeding mechanism including spring operating means carried solely by the carriage and connecting with said feed mechanism to exert a constant tensioned, traveling movement of said carriage, space-controlling mechanism, an actuating-lever member connecting with said space-controlling mechanism and constructed to permit actuation of the same, a laterally-traveling member adapted to be moved into the path of said lever member whereby, upon engaging the same, the carriage is permitted to have limited forward travel, an independent key member mounted on the laterally-traveling member and constructed to actuate said space-controlling mechanism to disengage it from said feed mechanism and permit free backward or forward travel of the carriage, substantially as described. 15
3. In a writing-machine, the combination of a flat platen, track-rails disposed adjacent thereto, a carriage mounted to travel longitudinally on said tracks, carriage - feeding mechanism including spring operating means carried solely by the carriage and connecting with said feed mechanism to exert a constant tensioned, traveling movement of said carriage, space-controlling mechanism, an actuating-lever member connecting with said space-controlling mechanism and constructed to permit actuation of the same, a laterally-traveling member adapted to be moved into the path of said lever member whereby, upon engaging the same, the carriage is permitted to have limited forward travel, an independent key member mounted on the laterally-traveling member and constructed to actuate said space-controlling mechanism to disengage it from said feed mechanism and permit free backward or forward travel of the carriage, and means independent of said actuating-lever and key member and constructed to vary the size of its spacing, substantially as described. 30
4. In a writing-machine, the combination of a flat platen, track-rails supported adjacent thereto, a longitudinally - traveling carriage supported on said track-rails, feed mechanism mounted solely on said carriage and adapted to travel therewith, said feed mechanism comprising spring operating means also entirely carried by the carriage and constructed to exert a constant tensioned movement on said feed mechanism to produce forward travel of the carriage, dog members, an escape-wheel, means connecting with said dog members and constructed to effect engagement thereof with the escape-wheel, spring actuating means adapted to reposition said dog members after actuation, and a stop member constructed to be positioned in the path of a dog member to vary the size of the spacing of said feed mechanism. 45
5. In a writing-machine, the combination of a flat platen and track - rails supported adjacent thereto, a carriage mounted to travel on said rails, feed mechanism carried entirely by said carriage and constructed to effect limited spacing thereof along the rails, a resilient member connecting with, and constructed to actuate, said feed mechanism, manually - operated means constructed to vary the tension of said spring member, said feed mechanism comprising a plurality of dog members constructed to be actuated in planes one different from the other, and a stop member arranged to be positioned in the path of one of said dog members whereby the size of spacing of the feed mechanism is changed. 70
6. In a writing-machine, the combination of a platen, track-rails supported adjacent said platen, a carriage mounted to travel on said rails, feed mechanism carried by said carriage including spring-controlled means also disposed on and movable with and constructed to effect spacing thereof along the rails, writing mechanism movably supported on said carriage, and means carried by said writing mechanism and arranged automatically to actuate said feed mechanism upon movement of said writing mechanism, substantially as described. 75
7. In a writing-machine, the combination with a horizontally-traveling carriage, gear-wheels mounted on either side of the carriage and constructed to rotate in unison and effect horizontal movement thereof, independent power means for rotating said gear-wheels, means for controlling the rotation of said gear-wheels and constructed to permit step-by-step movement of the same, means for varying the power of said propelling means, and means for maintaining said propelling means under a predetermined power, when varied, substantially as described. 80
8. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 85
9. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for limiting the extent of travel of said gear-wheels, substantially as described. 90
10. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 95
11. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 100
12. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 105
13. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 110
14. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 115
15. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 120
16. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 125
17. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, means for varying the power of said propelling means, means for maintaining said propelling means under a predetermined power, when varied, and means for increasing the extent of travel of said gear - wheels, substantially as described. 130

33. In a writing-machine, the combination with a horizontally-traveling carriage, gear-wheels mounted on the carriage and constructed to effect horizontal movement thereof, power means for rotating said gear-wheels, means for controlling the rotation of said gear-wheels and constructed to permit step-by-step movement of the same, and means for controllably varying the extent of travel of said gear-wheels, substantially as described.

34. In a writing-machine, the combination with a horizontally-traveling carriage, gear-wheels mounted on the carriage and constructed to effect horizontal movement thereof, independent power means for rotating said gear-wheels, means for intermittently stopping rotation of said gear-wheels in their travel, and means for increasing and decreasing the extent of travel of said gear-wheels, substantially as described.

35. In a writing-machine, the combination with a horizontally - traveling carriage, a transversely - traveling writing mechanism supported thereby, a gear-wheel mounted on the carriage and constructed to effect horizontal movement thereof, power means carried by the carriage and connecting with the gear-wheel for effecting movement thereof, reciprocable dog mechanism arranged in proximity to said gear-wheel and constructed to control the rotation thereof for step-by-step spacing of the carriage, and an actuator member connecting with said dog members and constructed to effect reciprocation of said dog members.

36. In a writing-machine, the combination with a horizontally - traveling carriage, a transversely - traveling writing mechanism supported thereby, a gear-wheel mounted on the carriage and constructed to effect horizontal movement thereof, power means carried by the carriage and connecting with the gear-wheel for effecting movement thereof, reciprocable dog mechanism arranged in proximity to said gear-wheel and constructed to control the rotation thereof for step-by-step spacing of the carriage, an actuator member connecting with said dog members and constructed to effect reciprocation of said dog members, and means carried by said writing mechanism for engaging said actuating-lever and constructed to operate the same.

37. In a writing-machine, the combination with a horizontally-traveling carriage, comprising a standard at opposite sides, track-rails upon which said carriage travels, wheels mounted on the standards of the carriage and constructed to engage said rails to effect horizontal travel of the carriage, power means for rotating said wheels in unison, mechanism for actuating said power means to effect rotation of the wheels and movement of the carriage, and rollers carried by the carriage and arranged to engage a plurality of surfaces of

said rails whereby the carriage is steadied and held against vibration.

38. In a writing-machine, the combination with a horizontally - traveling carriage, comprising a standard at opposite sides, track-rails upon which said carriage travels, feed-racks mounted on the rails, wheels disposed on the standards of the carriage and constructed to engage the feed - rack, power means for rotating said wheels in unison, rollers constructed to engage the upper and lower surfaces of said rails whereby said carriage is held against vibration during its travel upon said rails.

39. In a writing-machine, the combination with a horizontally - traveling carriage, a wheel carried by the carriage and constructed to effect horizontal movement thereof, power means carried by the carriage and connecting with the wheel and constructed to effect rotation thereof, a ratchet-wheel disposed adjacent to said wheel, and dog-plates constructed to be actuated in directions different one from the other, and coöperating with the ratchet-wheel and constructed to engage the ratchet-wheel and permit intermittent rotation of said ratchet-wheel, substantially as described.

40. In a writing-machine, the combination with a horizontally - traveling carriage, a wheel carried by the carriage and constructed to effect horizontal movement thereof, power means carried by the carriage and connecting with the wheel and constructed to effect rotation thereof, a ratchet-wheel disposed adjacent to said wheel, dog-plates constructed to be actuated in directions different one from the other, and coöperating with the ratchet-wheel and constructed to engage the ratchet-wheel and permit intermittent rotation of said ratchet-wheel, and means for effecting movement of said dog-plates to cause them to engage the ratchet-wheel, substantially as described.

41. In a writing-machine, the combination with a horizontally - traveling carriage, a wheel carried by the carriage and constructed to effect horizontal movement thereof, power means carried by the carriage and connecting with the wheel and constructed to effect rotation thereof, a ratchet-wheel disposed adjacent to said wheel, dog-plates coöperating with the ratchet-wheel and constructed to engage the ratchet-wheel and permit intermittent rotation of said ratchet-wheel, means for effecting movement of said dog-plates to cause them to engage the ratchet-wheel, and means arranged in juxtaposition to, and in position to engage, one of said dog-plates and constructed to increase and decrease the extent of movement of said dog-plates, substantially as described.

42. In a writing-machine, the combination with a horizontally - traveling carriage, a

wheel carried by the carriage and constructed to effect horizontal movement thereof, power means carried by the carriage and connecting with the wheel and constructed to effect 5 rotation thereof, a ratchet-wheel disposed adjacent to said wheel, dog-plates constructed to be actuated in directions different one from the other, and coöperating with the ratchet-wheel and constructed to engage the 10 ratchet-wheel and permit intermittent rotation of said ratchet-wheel, means for effecting movement of said dog-plates to cause them to engage the ratchet-wheel, and means for returning the dog-plates to normal position 15 after engagement with the ratchet-wheel, substantially as described.

43. In a writing-machine, the combination with a horizontally - traveling carriage, a gear-wheel carried by the carriage, power 20 means also carried by the carriage and connected with the gear-wheel and constructed to effect rotation thereof, a ratchet-wheel mounted contiguous to said gear-wheel, a plurality of dog-plates constructed to be actuated in directions different one from the other, and adjacent to said ratchet-wheel and constructed to engage the same intermittently, and means for effecting movement 25 of the dog-plates to cause engagement thereof with the ratchet-wheel, and means for returning the dog-plates to normal position, substantially as described.

44. In a writing-machine, the combination with a horizontally - traveling carriage, a gear-wheel mounted on the carriage, power means also mounted on the carriage and traveling therewith and constructed to effect rotation of the gear-wheel, a ratchet-wheel disposed adjacent to the gear-wheel, dog-plates movable toward and away from each other and constructed alternately to engage the ratchet-wheel, and means for supporting and guiding the dog-plates in their movement, substantially as described.

45. In a writing-machine, the combination with a horizontally - traveling carriage, a gear-wheel mounted on the carriage, power means also mounted on the carriage and traveling therewith and constructed to effect rotation 50 of the gear-wheel, a ratchet-wheel disposed adjacent to the gear-wheel, two dog-plates, one being reciprocable horizontally toward and away from the gear-wheel, and the other having movement away from its normal position, and means for guiding said second dog-plate for such movement, substantially as described.

46. In a writing-machine, the combination with a horizontally - traveling carriage, a gear-wheel mounted on the carriage, power means also mounted on the carriage and traveling therewith and constructed to effect rotation of the gear-wheel, a ratchet-wheel disposed adjacent to the gear-wheel, two dog-plates, 55 one being reciprocable horizontally toward

and away from the gear-wheel, and the other having movement away from its normal position, means for guiding said second dog-plate for such movement, and means for engaging said second plate for raising the same 70 out of its normal position, substantially as described.

47. In a writing-machine, the combination with a horizontally - traveling carriage, a gear-wheel mounted on the carriage, power means also mounted on the carriage and traveling therewith and constructed to effect rotation of the gear-wheel, a ratchet-wheel disposed adjacent to the gear-wheel, two dog-plates, 75 one being reciprocable horizontally toward and away from the gear-wheel, and the other having movement away from its normal position, means for guiding said second dog-plate for such movement, means for engaging said second plate for raising the same out of its 80 normal position, and means for returning said second plate to its normal horizontal position, substantially as described.

48. In a writing-machine, the combination with a horizontally - traveling carriage, a gear-wheel mounted on the carriage, power means also mounted on the carriage and traveling therewith and constructed to effect rotation of the gear-wheel, a ratchet-wheel disposed adjacent to the gear-wheel, two dog-plates, 90 one being reciprocable horizontally toward and away from the gear-wheel, and the other having movement away from its normal position, means for guiding said second dog-plate for such movement, means for engaging said second plate for raising the same out of its 95 normal position, and means for returning said second plate to its normal horizontal position, and means for limiting the movement of said second plate, substantially as described.

49. In a writing-machine, the combination with a horizontally - traveling carriage, a gear-wheel mounted on the carriage, power means also mounted on the carriage and traveling therewith and constructed to effect rotation of the gear-wheel, a ratchet-wheel disposed adjacent to the gear-wheel, a rigid dog-plate and a loose dog-plate connecting with and movable on each other, one of the plates having horizontal movement toward and away from the ratchet-wheel and the other of said plates having a movement at an angle to its normal position, and means for effecting engagement of the plates, alternately, with the 105 ratchet-wheel, substantially as described.

50. In a writing-machine, the combination with a horizontally - traveling carriage, a gear-wheel mounted on the carriage, power means also mounted on the carriage and traveling therewith and constructed to effect rotation of the gear-wheel, a shaft to which the gear-wheel is keyed, a horizontally-reciprocable plate, a dog carried thereby and constructed to engage the ratchet-wheel, a second plate 110 115 120 125 130

- connecting with the first-named plate, a yoke formed on said second plate and constructed to bear on said shaft, and means for positioning said plates and constructed to effect alternate engagement thereof with said ratchet-wheel, substantially as described.
51. In a writing-machine, the combination with a horizontally-traveling carriage, a gear-wheel mounted on the carriage, power means also mounted on the carriage and traveling therewith and constructed to effect rotation of the gear-wheel, a ratchet-wheel connecting with the gear-wheel, a slidable dog-plate disposed between the gear-wheel and ratchet-wheel, means for retaining said slidable plate in normal position, a downwardly-swinging plate connecting with said slidable plate and constructed to draw said slidable plate into engagement with the ratchet-wheel, and means carried by said downwardly-swinging plate for permitting movement thereof independent of the slidable plate, substantially as described.
52. In a writing-machine, the combination with a horizontally-traveling carriage, a gear-wheel mounted on the carriage, power means also mounted on the carriage and traveling therewith and constructed to effect rotation of the gear-wheel, a ratchet-wheel connecting with the gear-wheel, a slidable dog-plate disposed between the gear-wheel and ratchet-wheel, means for retaining said slidable plate in normal position, a downwardly-swinging plate connecting with said slidable plate and constructed to draw said slidable plate into engagement with the ratchet-wheel, means carried by said downwardly-swinging plate for permitting movement thereof independent of the slidable plate, and a lever device connecting with said downwardly-swinging plate and constructed to effect movement thereof, substantially as described.
53. In a writing-machine, the combination with a horizontally-traveling carriage, a gear-wheel mounted on the carriage, power means also mounted on the carriage and traveling therewith and constructed to effect rotation of the gear-wheel, a ratchet-wheel connecting with the gear-wheel, a slidable dog-plate disposed between the gear-wheel and ratchet-wheel, means for retaining said slidable plate in normal position, a downwardly-swinging plate connecting with said slidable plate and constructed to draw said slidable plate into engagement with the ratchet-wheel, means carried by said downwardly-swinging plate for permitting movement thereof independent of the slidable plate, a lever device connecting with said downwardly-swinging plate and constructed to effect movement thereof, substantially as described.
54. In a writing-machine, the combination with a horizontally-traveling carriage, a gear-wheel mounted on the carriage, power means also mounted on the carriage and traveling therewith and constructed to effect rotation of the gear-wheel, a ratchet-wheel connecting with the gear-wheel, a slidable dog-plate disposed between the gear-wheel and ratchet-wheel, means for retaining said slidable plate in normal position, a downwardly-swinging plate connecting with said slidable plate and constructed to draw said slidable plate into engagement with the ratchet-wheel, means carried by said downwardly-swinging plate for permitting movement thereof independent of the slidable plate, a lever device connecting with said downwardly-swinging plate and constructed to effect movement thereof, substantially as described.
55. In a writing-machine, the combination with a horizontally-traveling carriage, a gear-wheel mounted on the carriage, power means also mounted on the carriage and traveling therewith and constructed to effect rotation of the gear-wheel, a ratchet-wheel connecting with the gear-wheel, a slidable dog-plate disposed between the gear-wheel and ratchet-wheel, means for retaining said slidable plate in normal position, a downwardly-swinging plate connecting with said slidable plate and constructed to draw said slidable plate into engagement with the ratchet-wheel, means carried by said downwardly-swinging plate for permitting movement thereof independent of the slidable plate, a lever device connecting with said downwardly-swinging plate and constructed to effect movement thereof, and a tripper-arm co-operating with said lever and constructed to actuate the same to effect movement of the downwardly-swinging plate, substantially as described.
56. In a writing-machine, the combination with a horizontally-traveling carriage, a gear-wheel mounted on the carriage, power means also mounted on the carriage and traveling therewith and constructed to effect rotation of the gear-wheel, a ratchet-wheel disposed adjacent to the gear-wheel, a slidable dog-plate constructed to engage the ratchet-wheel, a downwardly-swinging dog-plate connecting with the slidable plate and constructed to engage the ratchet-wheel, and means disposed in the path of the downwardly-swinging plate and constructed to limit the swing thereof, substantially as described.
57. In a writing-machine, the combination with a horizontally-traveling carriage, a gear-wheel mounted on the carriage, power means also mounted on the carriage and traveling therewith and constructed to effect rotation of the gear-wheel, a ratchet-wheel disposed adjacent to the gear-wheel, a slidable dog-plate constructed to engage the ratchet-wheel, a downwardly-swinging dog-plate connecting with the slidable plate and constructed to engage the ratchet-wheel, means disposed in the path of the downwardly-swinging plate and constructed to limit the swing thereof for single spacing, and means for adjusting said limiting means to increase the swing of said plate for double or larger spacing, substantially as described.
58. In a writing-machine, the combination with a horizontally-traveling carriage, a gear-wheel mounted on the carriage, power means also mounted on the carriage and traveling therewith and constructed to effect rotation of the gear-wheel, a ratchet-wheel disposed adjacent to the gear-wheel, a slidable dog-plate constructed to engage the ratchet-wheel, a downwardly-swinging dog-plate connecting with the slidable plate and constructed to engage the ratchet-wheel, means disposed in the path of the downwardly-swinging plate and constructed to limit the swing thereof for single spacing, and means for adjusting said limiting means to increase the swing of said plate for double or larger spacing, substantially as described.

disposed in the path of the downwardly-swinging plate and constructed to limit the swing thereof, and an adjusting-stop for limiting the swing of the downwardly-swinging plate and constructed to adjust the same for single, double or larger spacing, substantially as described.

58. In a writing-machine, the combination with a horizontally-traveling carriage, a gear-wheel mounted on the carriage, power means also mounted on the carriage and traveling therewith and constructed to effect rotation of the gear-wheel, a ratchet-wheel disposed adjacent to the gear-wheel, a slideable dog-plate constructed to engage the ratchet-wheel, a downwardly-swinging dog-plate connecting with the slideable plate and constructed to engage the ratchet-wheel, means disposed in the path of the downwardly-swinging plate and constructed to limit the swing thereof, an adjusting - stop for limiting the swing of the downwardly-swinging plate and constructed to adjust the same for single, double or larger spacing, and means for effecting disengagement of both plates from the ratchet-wheel to permit free travel of the carriage.

59. In a writing-machine, the combination with a horizontally-traveling carriage, a gear-wheel mounted on the carriage, a shaft upon which the gear-wheel is keyed, a second gear-wheel, a lantern-pinion engaging said second gear-wheel and constructed and arranged to cause rotation of said second gear-wheel and, also, to hold the same in a locked position, a ratchet-wheel, and dog mechanism engaging therewith, substantially as described.

60. In a writing-machine, the combination with a horizontally-traveling carriage, a gear-wheel mounted on the carriage, a second gear-wheel arranged in a plane parallel with the first-named gear-wheel, a shaft on which the first-named gear-wheel is keyed, a spring connecting with said shaft and said second gear-wheel and interposed between the two said gear-wheels and constructed to effect rotation of said shaft and said first-named gear-wheel, a ratchet-wheel, and dog mechanism constructed to engage therewith, substantially as described.

61. In a writing-machine, the combination with a horizontally-traveling carriage, a gear-wheel mounted on the carriage, a second gear-wheel arranged in a plane parallel with the first-named gear-wheel, a shaft on which the first-named gear-wheel is keyed, a spring connecting with said shaft and said second gear-wheel and interposed between the two said gear-wheels and constructed to effect rotation of said shaft and said first-named gear-wheel, a ratchet-wheel, and dog mechanism constructed to engage therewith, and means for tensioning said spring, substantially as described.

65 62. In a writing-machine, the combination

with a horizontally-traveling carriage, a gear-wheel mounted on the carriage, a second gear-wheel arranged in a plane parallel with the first-named gear-wheel, a shaft on which the first-named gear-wheel is keyed, a spring connecting with said shaft and said second gear-wheel and interposed between the two said gear-wheels and constructed to effect rotation of said shaft and said first-named gear-wheel, a ratchet-wheel, and dog mechanism constructed to engage therewith, means for tensioning said spring, and means for maintaining said spring under such tension, substantially as described.

63. In a writing-machine, the combination with a horizontally-traveling carriage comprising side standards, a transverse shaft extending between said standards, gear-wheels keyed to said shaft and housed within said standards, power means also housed within said standards and connected with said shaft and arranged to travel with said standards and constructed to effect rotation of the shaft and gear-wheels, and dog mechanism housed in said standards and constructed to control rotation of the shaft.

64. In a type-writer, the combination with a flat platen, a transversely-movable carriage, a longitudinally-movable carriage supporting the transversely-movable carriage, dog mechanism carried by the transversely-movable carriage, means for effecting general release of said dog mechanism to permit free travel transversely of said carriage, dog mechanism carried by the longitudinally-movable carriage, means for effecting general release of said dog mechanism to permit free travel of said longitudinally-movable carriage, said general release means being disposed adjacent to and operable independently of, but simultaneously with, said general release means of the transversely-movable carriage, substantially as described.

65. In a type-writer, the combination with a flat platen, a transversely-movable carriage, a longitudinally-movable carriage supporting the transversely-movable carriage, dog mechanism carried by the transversely-movable carriage, means for effecting general release of said dog mechanism to permit free travel transversely of said carriage, dog mechanism carried by the longitudinally-movable carriage, means for effecting general release of said dog mechanism to permit free travel of said longitudinally-movable carriage, said general release means being disposed adjacent to and operable independently of, but simultaneously with, said general release means of the transversely-movable carriage, and a handle disposed adjacent to both of said general release means and constructed to permit guiding of said carriages in all directions, at will, substantially as described.

66. In a type-writer, the combination with

- a flat platen, rails disposed adjacent thereto, a carriage movable over said rails, gear mechanism carried by said carriage, propelling means for rotating said gear mechanism, dog mechanism for controlling the rotation of said gear mechanism, a general release device constructed and arranged to effect free travel of said carriage, and a handle disposed adjacent to said general release device and constructed to permit guiding of the carriage, when released, substantially as described.
67. In a type-writer, a platen, tracks arranged contiguous thereto, a longitudinally-traveling carriage supported on said tracks, 15 guide-rails mounted on said carriage, a transversely-traveling carriage supported on said rails, spring-actuated propelling mechanism disposed on and movable with said longitudinally-traveling carriage, and means for controlling operation of said propelling mechanism, comprising reciprocable dog members carried by said longitudinally-traveling carriage, and means disposed contiguous to said dog members for reciprocating the same and 20 means for governing the distance of travel of said longitudinally-traveling carriage.
68. In a type-writer, a platen, tracks arranged contiguous thereto, a longitudinally-traveling carriage supported on said tracks, 25 guide-rails mounted on said carriage, a transversely-traveling carriage supported on said rails, spring-actuated propelling mechanism disposed on and movable with said longitudinally-traveling carriage, reciprocable dog members carried by said longitudinally-traveling carriage, and means disposed contiguous to said dog members for reciprocating the same and a general release device for effecting free travel of said carriage longitudinally.
69. In a type-writer, a platen, tracks arranged contiguous thereto, a longitudinally-traveling carriage supported on said tracks, 30 guide-rails mounted on said carriage, a transversely-traveling carriage supported on said rails, spring-actuated propelling mechanism disposed on and movable with said longitudinally-traveling carriage, reciprocable dog members carried by said longitudinally-traveling carriage, and means disposed contiguous to said dog members for reciprocating the same and a general release device, disposed on the transversely-traveling carriage and constructed for effecting free travel of said carriage longitudinally.
70. In a type-writer, tracks, a feed-rack, a carriage having longitudinal travel on the tracks, rails disposed on said carriage, a transversely-traveling carriage supported on said rails, feed mechanism disposed on and movable with said longitudinally-traveling carriage and comprising a plurality of reciprocable dog members, one having movement independent of the other, means for reciprocating said dog members and a device disposed in the path of travel of the trans- 35 versely-traveling carriage and constructed to be impinged by said carriage and operate said feed mechanism.
71. In a type-writer, tracks, a feed-rack, a carriage having longitudinal travel on said tracks, rails disposed on said carriage, a transversely-traveling carriage supported on said rails, feed mechanism disposed on and movable with said longitudinally-traveling carriage, comprising a plurality of reciprocable dog members an arm connecting with said feed mechanism and constructed to actuate the same, and a cam device disposed on said transversely-traveling carriage and constructed to actuate said arm and effect spacing of the longitudinally-traveling carriage.
72. In a type-writer, tracks, a feed-rack, a carriage having longitudinal travel on said tracks, rails disposed on said carriage, a transversely-traveling carriage supported on said rails, feed mechanism comprising a plurality of oscillating dog members, one of said dog members arranged to have a horizontal movement only, the other of said dog members arranged to be oscillated vertically and horizontally, and an escape - wheel with which said dog members engage, said feed mechanism disposed on and movable with said longitudinally-traveling carriage, an arm connecting with said feed mechanism, a cam device disposed on said transversely-traveling carriage and constructed to actuate said arm and effect spacing of the longitudinally-traveling carriage, and means for changing the extent of operation of said feed mechanism to produce a greater or less movement of said carriage.
73. In a type-writer, tracks, a feed-rack, a carriage having longitudinal travel on said tracks, rails disposed on said carriage, a transversely-traveling carriage supported on said rails, feed mechanism disposed on and movable with said longitudinally-traveling carriage, an arm connecting with said feed mechanism, a cam device disposed on said transversely - traveling carriage, and constructed to actuate said arm and effect spacing of the longitudinally-traveling carriage, and a second arm also connecting with the feed mechanism and constructed also to effect spacing of the longitudinally-movable carriage.
74. In a type-writer, tracks, a feed-rack, a carriage having longitudinal travel on said tracks, rails disposed on said carriage, a transversely-traveling carriage supported on said rails, feed mechanism disposed on and movable with said longitudinally-traveling carriage, an arm connecting with said feed mechanism, a cam device disposed on said transversely - traveling carriage and constructed to actuate said arm and effect spacing of the longitudinally-traveling carriage, a second arm also connecting with the feed mechanism and constructed also to effect spacing of the longitudinally-movable carriage.

spacing of the longitudinally-movable carriage, and means for varying the spacing of said carriage.

75. In a type-writer, tracks, a feed-rack, a carriage having longitudinal travel on said tracks, rails disposed on said carriage, a transversely-traveling carriage supported on said rails, feed mechanism disposed on and movable with said longitudinally-traveling carriage, an arm connecting with said feed mechanism, a cam device disposed on said transversely-traveling carriage and constructed to actuate said arm and effect spacing of the longitudinally-traveling carriage, a second arm also connecting with the feed mechanism and constructed also to effect spacing of the longitudinally-movable carriage, means for varying the spacing of said carriage, and means engaging the feed mechanism and constructed to effect free travel of the carriage longitudinal on its supporting-tracks.

76. In a type-writer, tracks, a feed-rack, mounted contiguous thereto, a carriage having longitudinal travel along said tracks, dog mechanism mounted on and traveling with said carriage, and engaging with the feed-rack, a laterally-traveling carriage supported by the first-named carriage, a feed-rack disposed adjacent to the carriage, dog mechanism mounted on and traveling with said transversely-traveling carriage and engaging second-named rack, means for effecting disengagement of the dog mechanism of the longitudinally-traveling carriage, independent means for disengaging the dog mechanism of the laterally-traveling carriage, the two disengaging means being constructed and arranged to be simultaneously but independently operated, and a carriage-guiding handle constructed and arranged to effect positioning of either or both carriages when their dog mechanism is disengaged.

77. In a type-writer, movable track-rails, a carriage movable longitudinally thereon, propelling mechanism for moving said carriage, escapement means mounted on carriage to control said propelling means, and means for guiding and positioning the track-rails when said rails are being returned to normal position after being moved.

78. In a type-writer, tiltable track-rails, a carriage thereon having longitudinal movement, propelling mechanism for moving said carriage, escapement mechanism mounted on carriage to control said propelling means, means for actuating said escapement automatically and by hand, and means for guiding and positioning the track-rails.

- 60 79. In a type-writer, tiltable track-rails, a carriage thereon having longitudinal movement, propelling means for moving said carriage, escapement mechanism mounted on carriage to control said propelling means,

means for actuating said escapement automatically and by hand, means for adjusting escapement for different widths of spacing, and means for guiding and positioning the track-rails.

80. In a type-writer, a longitudinally-traveling carriage, tracks which the carriage traverses, dog mechanism carried by and traveling with the carriage and comprising a plurality of dog-carrying plates mounted in juxtaposition one with the other, a general-release device connecting with one of the dog-plates and constructed to shift the same, and means for retaining the other dog-plate in normal position during the operation of the general release device, whereby advance movement of the carriage is prevented.

81. In a type-writer, a longitudinally-traveling carriage, a track which is traversed by the carriage, a toothed member engaging said track, a shaft upon which said member is keyed, a ratchet-wheel also keyed on said shaft, a rigid dog-plate designed to engage the ratchet-wheel and provided with a slot, a loose dog-plate alternately in engagement with the ratchet-wheel and provided with a pin designed to work in said slot, a general release device constructed to withdraw the loose dog from engagement with the ratchet-wheel, and means for maintaining the loose dog in position during operation of the general release.

82. In a type-writer, the combination with longitudinally-adjustable track-rails, a stationary supporting member for sustaining said rails at the rear, a longitudinally-traveling carriage constructed to traverse said rails, feed mechanism constructed to effect intermittent spacing of said carriage on the rails, and an adjusting device disposed independent of said feed mechanism and constructed to effect longitudinal adjustment of the track-rails upon said stationary supporting member.

83. In a type-writer, the combination with a flat platen, track-rails disposed contiguous to and longitudinally of the same, a longitudinally-traveling carriage comprising supporting-standards adapted to traverse said rails, line-spacing mechanism disposed in said standards, brackets formed on said standards and overlying the platen, transversely-extending guide-rails supported on said bracket, and a laterally-traveling carriage suspended on said guide-rails and constructed to be moved across the platen independent of the movement of the longitudinally-traveling carriage.

84. In a type-writer, a flat platen, track-rails arranged longitudinally thereof, a longitudinally-traveling carriage comprising side standards having an enlarged base portion to constitute a housing and provided with overhanging brackets, guide-rails supported by

said brackets, and a transversely-movable carriage suspended on said brackets and in a plane in advance of the side standards, said carriage being constructed to have movement independent of the movement of the longitudinally-traveling carriage, and said latter carriage being constructed to position the transversely-movable carriage, for line-spacing.

85. In a type-writer, a longitudinally-traveling carriage, tracks constructed to be traversed by said carriage, said carriage comprising supporting-standards provided with an enlarged base, a housing constituted on said standards, dog mechanism housed within said standards, overhanging brackets formed at the upper portion of said standards, guide-rails supported on said brackets, and a transversely-movable carriage constructed to be suspended from and movable on said guide-rails, and arranged to have travel, transversely of the tracks.

86. In a type-writer, the combination with a longitudinally-traveling carriage, of tracks provided with flanges, said carriage comprising standards having enlarged lower portions, and provided at their upper portions with overhanging brackets, rollers carried by the enlarged portions of the standards and engaging the flanges on the tracks, guide-rails supported on the brackets, and a transversely-movable carriage suspended from said guide-rails and constructed to traverse the same for letter-spacing.

87. In a type-writer, the combination with a longitudinally-traveling carriage, tracks constructed to be traversed by said carriage, a flat platen underlying said carriage, the said carriage comprising standards with enlarged base portions and provided with brackets at their upper portions, guide-rails supported on said brackets, a transversely-movable carriage constructed to traverse said guide-rails, and arranged to be moved to either side of the platen without interfering with the position of the longitudinally-traveling carriage.

88. In a type-writer, the combination with a longitudinally-movable carriage comprising a plurality of side standards, each constituting a housing, dog mechanism disposed in said housing, gear-wheels disposed on said standards, a transverse shaft connecting said gear-wheels and constructed to effect rotation of the same in unison, a transversely-traveling carriage supported on said longitudinally-traveling carriage, in advance of said standards, and a lever connecting with said dog mechanism and constructed to be actuated by the transversely-traveling carriage.

89. In a type-writer, track-rails, a longitudinally-traveling carriage constructed to traverse said track-rails comprising side standards, a transversely-traveling carriage

suspended from said standards, dog members supported on said standards, a gear-wheel disposed contiguous to said dog members, an escape-wheel mounted adjacent to said dog members, a shaft upon which said gear-wheel and escape-wheel are disposed, a lever connecting with said dog members and constructed to actuate the same for rotation of the gear-wheel, and means carried by the transversely-traveling carriage for effecting movement of said lever, for line-spacing.

90. In a type-writer, track-rails, a longitudinally-traveling carriage constructed to traverse said track-rails and comprising side standards, a transversely-traveling carriage suspended from said standards, dog members supported on said standards, a gear-wheel disposed contiguous to said dog members, an escape-wheel mounted adjacent to said dog members, a shaft upon which said gear-wheel and escape-wheel are disposed, a lever connecting with said dog members and constructed to actuate the same for rotation of the gear-wheel, means carried by the transversely-traveling carriage for effecting movement of said lever, for line-spacing, and means disposed contiguous to said dog members and constructed to be operated to vary the extent of space movement of said gear-wheel.

91. In a type-writer, an automatically-actuated, longitudinally-traveling carriage comprising side standards, a transversely-traveling carriage suspended in advance of said standards, dog members mounted on said standards, a gear-wheel arranged contiguous to said dog members, an escape-wheel mounted adjacent to said dog members, a shaft upon which said gear-wheel and escape-wheel are mounted, power means also supported on said standards and engaging said shaft, and means for automatically actuating said longitudinally-traveling carriage, for space movement, and means for adjusting said dog members for effecting different widths of line-spacing when said longitudinally-traveling carriage is automatically actuated.

92. In a type-writer, an automatically-actuated, longitudinally-traveling carriage comprising side standards, a laterally-traveling member supported by said standards, dog mechanism disposed on one of said standards and comprising a plurality of oscillating dog-plates, an actuating-arm connecting with said dog-plates and constructed to move the same and cause travel of the carriage for line-spacing, and an adjusting member constructed to be positioned in and out of the path of movement of one of said dog members for changing the travel of the carriage.

93. In a type-writer, an automatically-actuated, longitudinally-traveling carriage

- comprising side standards, a laterally-traveling member supported by said standards, dog mechanism disposed on one of said standards and comprising a plurality of oscillating 5 dog-plates, an actuating-arm connecting with said dog-plates and constructed to move the same and cause travel of the carriage for line-spacing, an adjusting member constructed to be positioned in and out of the 10 path of movement of one of said dog members for changing the travel of the carriage, and means connecting with said dog members, independent of the actuating-arm, for effecting free travel of said carriage.
- 15 94. In a type-writer, a longitudinally-traveling carriage, a feed-rack disposed in the path of said carriage, dog mechanism carried by and movable with said carriage, power means carried by and movable with said carriage and constructed to exert a constant advance movement on said carriage and prevent rebound of same, when actuated, means for controlling the movement of said dog mechanism, and means for automatically 20 actuating said dog mechanism.
95. In a type-writer, the combination with a longitudinally-traveling carriage, tracks constructed to be traversed by said carriage and carrying a feed-rack, spring-actuated 25 feed mechanism carried by said carriage and constructed to engage said feed-rack, an automatically-operating line-spacing device connecting with said feed mechanism, an adjusting member carried by said carriage and 30 having a plurality of abutting faces constructed to be moved to present one of its plurality of abutting faces in the path of movement of one of said dog members.
96. In a type-writer, the combination with 35 a longitudinally-traveling carriage comprising side standards, tracks constructed to be traversed by said standards, gears carried by said standards and adapted to engage said tracks, a transverse shaft connecting said 40 gears and extending between said standards, a power-spring connecting with said shaft, a rotatable toothed member with which said spring also connects, and a combined rotating and locking device engaging with said 45 toothed member.
97. In a type-writer, the combination with 50 a longitudinally-traveling carriage, comprising a plurality of side standards, means for rigidly supporting said standards one with relation to the other, a feed-rack disposed in 55 the path of travel of the carriage, gears carried by the standards and constructed to engage the feed-rack, feed mechanism constructed to govern the operation of said 60 gear-wheels, adjustable tracks movably supported at their rear and constructed to be traversed by said standards, and an adjusting-screw for adjusting said tracks longitudinally, simultaneously to position said car- 65 riage intermediate of the regular line-spacing thereof.
98. In a type-writer, the combination with a longitudinally-traveling carriage, tracks constructed to be traversed by said carriage, a feed-rack disposed in the path of travel of 70 said carriage, a gear carried by said carriage and adapted to mesh with said feed-rack, a shaft connecting with said gear, power-springs connecting with said shaft, a rotatable member with which said springs also connect and adapted to tension said springs, said springs being constructed and arranged relative to said shaft whereby, by movement of the carriage in a direction opposite to its travel for line-spacing, they are tensioned automatically. 75
99. In a type-writer, the combination with a flat platen, tracks normally arranged parallel with said platen and constructed to be tilted away therefrom, a pivotal support for 80 said tracks, racks carried by said tracks, a longitudinally-traveling carriage adapted to traverse said tracks, and constructed to be positioned to the rear of the pivotal point of the tiltable tracks and by its weight and that 85 of the tracks, balance said tracks about said pivotal support and dog mechanism carried by said carriage, adapted to engage said racks and arranged to effect locking of the carriage to the tracks when the carriage is to 90 the rear of the pivotal points of the tracks and said tracks are tilted. 95
100. In a writing-machine, the combination of a platen, track-rails supported adjacent said platen, a carriage mounted to travel on said rails, feed mechanism carried by said carriage, carriage-propelling means connecting with said feed mechanism and constructed to effect spacing thereof along the rails and disposed on and movable with 105 the carriage throughout its travel, a transversely-traveling writing mechanism movably supported on said carriage and constructed to be positioned manually at the starting-point of each writing-line, and 110 means carried by said traveling writing mechanism and arranged to engage with and operate said carriage-propelling means when so manually positioned at the starting-point of each writing-line and effect travel of said carriage in the direction of line-spacing. 115
101. In a writing-machine, the combination of a platen, track-rails supported adjacent said platen, a carriage mounted to travel on said rails, feed mechanism carried by said carriage, carriage-propelling means connecting with said feed mechanism and constructed to effect spacing thereof along the rails and disposed on and movable with 120 the carriage throughout its travel, means co-operating with said feed mechanism and constructed to vary the length of its spacing, 125 a transversely-traveling writing mechanism

movably supported on said carriage and constructed to be positioned manually at the starting-point of each writing-line, and means carried by said traveling writing mechanism 5 and arranged to engage with and operate said carriage-propelling means when so manually positioned at the starting-point of each writing-line and effect travel of said carriage

in the direction of line-spacing to the extent permitted by said space-varying means. 10

In testimony whereof I affix my signature in the presence of two subscribing witnesses.

GEORGE W. DONNING.
